SEWING MACHINE

Hans Hacklander, Linden, N. J., and George Sauer, Berwyn, Ill., assignors to Union Special Machine Company, Chicago, Ill., a corporation of Illinois

Application June 22, 1937, Serial No. 149,594

6 Claims. (Cl. 184—6)

This invention relates to sewing machines, and it has reference more particularly to feed-off-the-arm sewing machines such as typified in U. S. Patent No. 1,741,095, granted to Norman V. Christensen and Harold J. Le Vesconte on December 24, 1929. In a machine of the kind specifically referred to, the drive shaft and its bearings and the needle actuating mechanism are enclosed within a hollow longitudinally-extending tubular elevated portion of the machine frame; while the complementary stitch-forming mechanism and the feeding mechanism are enclosed within a hollow underreaching work supporting arm and operated, through strap rods extending downwardly within a vertical tubular frame portion which connects the rear end of said work supporting arm with said elevated frame portion, by rotary eccentric actuators on said drive shaft. By virtue of the great number of moving parts within the elevated portion of the machine frame and to the inaccessibility of these parts, considerable time is consumed in properly oiling them; and if oiling is neglected through indifference or carelessness as often happens, rapid wear will ensue particularly when the machine is operated at high speeds, thereby necessitating either complete replacement of the worn parts or costly repairs.

Our invention has for its aim to obviate such contingencies, which desideratum we attain as 30 hereinafter more fully disclosed, by forming the drive shaft hollow and with lateral ports for capacity to conduct oil from a gravity supply reservoir to the shaft bearings and the rotary actuators, by incorporating in the frame structure 35 secondary sumps to receive the excess or overflow oil from the bearings from which different parts are lubricated by splash action, and by providing a main sump to receive the overflow from the secondary sumps, and means for lifting the oil accumulating in the main sump to the reservoir for re-passage through the machine.

Other objects and attendant advantages will appear from the following detailed description of the attached drawings, wherein Fig. I is a view 45 in side elevation of a feed-off-the-arm sewing machine conveniently embodying the present improvements, portions of the machine frame having been broken away to show the mechanism at the interior.

Fig. II is a plan view of the machine, likewise with portions of the frame broken out.

Fig. III is a fragmentary detail sectional view taken as indicated by the arrows III—III in Figs. I and II, and drawn to a larger scale.

Fig. IV is a fragmentary detail sectional view similarly drawn to a larger scale and taken as indicated by the arrows IV—IV in Fig. I.

Fig. V is a fragmentary detail sectional view on an enlarged scale taken as indicated by the arrows V—V in Fig. II.

Fig. VI is a longitudinal vertical sectional view through the work support arm of the machine showing the feeding and the auxiliary stitching mechanism; and

Fig. VII is a view partly in elevation and partly in horizontal section taken as indicated by the arrows VII—VII in Fig. VI.

The illustrated sewing machine has a frame 15 with a longitudinal tubular portion 1 sustained at an elevation by an integrally-formed bracket-like hollow supporting base 2, and a hollow arm-like work support 3 which communicates with said elevated portion at one end through a vertical tubular connecting portion 4. The free end of the work support 3 underreaches a hollow head 5 projecting laterally from the elevated frame portion 1 and detachably secured thereto by screws, one of which is shown at 6 in Fig. III. Extending longitudinally through the hollow of the elevated frame portion 1 is a drive shaft 7 which is journaled in bearing bushings 8, 9, 10 and 11 whereof the bushings 9 and 10 are set into cross-wise extending partitions 12 and 13 and the bushings 8 and 11 respectively set into the front and rear end walls 14 and 15 of said frame portion. To the front protruding end of the shaft 7 is secured a combined hand and belt wheel 16 whereby it can be operated either normally or by power. Guided for up and down movement in the head 5 is a vertical needle bar 17, which, at its lower end, carries a pair of needles 18, and which, as shown in Figs. I and III, is slidable in bushings 19 and 20, fixed respectively to the top and bottom walls 21 and 22 of said head. The needle bar 17 is in this instance actuated by means including a transverse shaft 23 which is journaled in a bearing boss 24 on the back wall 25 of the head 5, said boss extending through an offset 26 in the side wall 27 of the elevated tubular frame portion 1, see Figs. II and III, and rotary motion being imparted from the drive shaft 7 to said transverse shaft through a pair of bevel gears 28, 29. Affixed to the outer end of the transverse shaft 23 is a bell crank member 30 whereof the crank stud 31 is connected, by means of a pitman 32, with a stud projection 33 of a collar 34 secured to the needle bar 17 within the head 5. Incident to its endwise reciprocation, the

55 under the action of the means just described, the

needle bar 37 is restrained against rotation as a consequence of confinement of the outer end of the stud projection 38 on the collar 34 in the vertical slot 35 of a fixed guide 36 within the head 5, see Figs. I and III. The presser bar 37 of the machine has sliding guides near its lower end in a bearing bushing 38 set into the bottom wall 22 of the head 5, and near its top in a bearing lug 39 which reaches inward from one of the side walls of said head. By means of a leaf spring 40 whereof the outer or moving end, shown at 40 in Fig. I, the presser bar 37 is urged downward to maintain the presser foot 41 at the lower end thereof (Fig. I) in yielding contact with the fabric (not shown) which is sewed in the machine. Rotation of the presser bar 37 is prevented through engagement of the projection 42 of a collar 43 thereof with a vertical slot in another fixed guide block 44 within the head 5, see Fig. I. The complementary mechanism which cooperates with the needles 18 in the formation of seam stitches and the feeding mechanism of the machine are disposed within the hollow of the work support 3, as shown in Figs. VI and VII. They may be of the form disclosed in separate patents numbered 2,199,663 and 2,211,619 maturing from applications filed by us concurrently herewith, having various of their moving parts operated as presently explained through a series of strap rods 45 which extend downward of the vertical hollow 4 of the machine frame, by rotary eccentric actuators 46 affixed to the portion of the drive shaft 7 in the interval between the partition 13 and the rear wall 15 of the elevated tubular frame portion, as shown in Figs. I and II.

Referring to Figs. VI and VII, the complementary stitch-forming mechanism includes a looper 101 which is attached to the outer end of a horizontal shaft 102 suitably journaled in bearings 103, 104 and 105 within the hollow of the work arm 3. Secured to the shaft 102 in the interval between bearings 104 and 105 is a ball crank arm 106 whereto the eccentric strap rod 45b is connected at its lower end, and whereby oscillatory movements are induced in the shaft to impart needle-avoiding movements to the looper 101. Near its inner end the shaft 102 (Fig. VI) carries a swivel collar 107, which, by means of a horizontal link 108, is coupled with the pendant arm of a bell crank lever 109 freely fulcrumed on a cross pin 110. The horizontal arm of the bell crank lever 109 is in turn connected to the lower end of the eccentric strap rod 45d. As a consequence of this arrangement, the shaft 102 is reciprocated endwise for impartation of loop taking movements to the looper 101. Surrounding the shaft 102 is a sleeve 111, which, at its outer end, carries a spreader 112 to coact with the looper 101. As shown, the shaft 111 extends inward somewhat beyond the bearing 104, and to its protruding inner end is secured a ball arm 113 whereto the lower end of the eccentric strap rod 45 is connected to impart oscillatory movements to the sleeve 111 and the spreader 112 carried thereby.

The feeding mechanism of the machine comprises a feed dog 115 which operates upwardly through an apertured throat plate 116 at the top of the free end of the work supporting arm, and which is fixedly secured to the outer end of a feed bar 117 extending longitudinally of the hollow of said work support. Adjacent its front end, the feed bar 117 is confined against lateral movement in the longitudinal slot of a guide partition 118 extending crosswise of the hollow of the work

arm. Immediately inward of the partition 118 the feed bar 117 is coupled, by means of a vertical link 119, with the horizontal arm of a bell crank lever 120 fulcrumed on a fixed transverse pin 121. The upright arm of the bell crank lever 120 is in turn coupled, by means of a horizontal link 122, with a bell crank 123 fulcrumed to swing on a cross pin 124 extending crosswise of the work arm 3 at the rear end of the latter. To the horizontal extremity of the bell crank 123 is pivotally connected the lower end of the eccentric rod 45a. At its rear end the feed bar 117 is pivotally connected to the pendant arm of still another bell crank 125 free on the cross pin 110 which serves the bell crank 109 previously referred to, the horizontal arm of said bell crank lever 123 being pivotally connected to the lower end of the eccentric rod 45c. By this means, both horizontal or feeding movements and up and down or lift movements are imparted to the feed dog as required to intermittently advance the material outwardly along the work arm 3. For other details of the complementary stitch-forming and feeding mechanisms, reference may be had to the other co-pending applications hereinbefore referred to.

In order to adapt a machine such as has been briefly described to the purpose of our invention, provisions have been made as follows: Extending axially through the drive shaft 7 is a duct 47, which, it will be noted from Figs. I and II, is in communication at its rear end with a chamber 48 within the bore 49 for the bearing bushing 11, said chamber being closed at the back by a diaphragm 50. The lubricating oil flows by gravity into the shaft 7 from a supply reservoir 51 located within the hollow of the elevated longitudinal frame portion 1 above the eccentric actuators 46, see Fig. I. A conical nipple 52 on an elbow outlet tube 53 at the rear end of the reservoir 51 engages the mouth of a horizontal flow passage 54 in the wall 15 of the elevated frame portion 1, said passage having a vertical branch 55 which leads downward into the chamber 48, see Fig. I. Flow of the oil from the reservoir 51 is controlled by a submerged wick which reaches into the elbow outlet tube 53. Cooperating with the nipple 52 in holding the reservoir 51 in place is a screw bolt 56 whereof the shank threadedly engages a tapped hole 57 in the partition 13 and whereof the head bears against the front end of said reservoir. By virtue of this arrangement, the reservoir 51 may be removed for cleaning when required by backing off the screw bolt 56 after withdrawing a top cover 58 which closes the hollow in the rear of the elevated frame portion 1. Part of the oil thus received from the reservoir 51 flows through lateral ports 59, 60 and 61, into the bearings 8, 9 and 10 for the drive shaft 7, the rear bearing 11 being lubricated as a consequence of being exposed directly within the chamber 48. As shown in Fig. I, the shaft is also provided with a series of lateral ports 62 which lead to annular clearances 63 within the rotary eccentric actuators 46. From these clearances 63, the oil flows through lateral ports 64 in the rotary actuators 46 to the spherical surfaces of the latter. The front end wall 14 of the elevated tubular portion 1 of the machine frame is formed with an annular recess 65 in concentric relation to the axis of the shaft 7, which recess is closed by a plate 66 apertured for passage of the hub 67 of the combined end wheel and pulley 16. The well 68 thus formed receives the excess or overflow oil from

the bearing 8. The overflow oil from the bearing 9 is received in a sump 69 at the bottom of a housing 70 for the gears 28 and 29 within the elevated tubular portion 1 of the frame. As shown in Fig. III, the housing 70 is defined by the end wall 14, the partition 12, the offset 26 of the side wall 27 of said elevated frame portion, and by a supplemental wall or partition 71. The overflow of oil from the well 68 for the front bearing 8 for the shaft 7 also drains into the sump 69 by way of a by pass 68a in the end wall 14, see Figs. I and II. The housing 70 is closed at the top by a cover plate 12 (Fig. III) which is removably secured by screws 13 and which is in turn accessible upon removal of a top cover section 74 closing the hollow of the elevated frame portion 1 rearward of the head 5, the cover section being likewise secured by screws 75. As shown in Fig. III, the gears 28 and 29 dip into the oil within the sump 69 and are thus lubricated by a splash action. Some of the oil thus lifted by the gears 28, 29 finds its way to a port 76 in the top of the bearing boss 24 and thus lubricates the spaced bearing bushings 78, 79 for said shaft. The oil which accumulates in the sump 69 drains by way of a tubular dowel pin 80 (Fig. III) into a sump 81 in the bottom of the head 5. By means of a disk 82 attached to the balanced crank member 30 and dipping into the oil in the sump 81, oil is distributed in the form of a mist over the needle bar actuating parts within the head 5 as well as over the parts associated with the presser bar 37. In order to further insure adequate lubrication of the pin bearings for the pitman 32, the latter is formed with a longitudinal duct 83, and with a communicating oil scoop 84 at its lower end, see Figs. I and III. Overflow oil from the sump 81 in the head 5 drains by way of ports 85 and 86 respectively in the partitions 12 and 13 into a main sump 87 within the rear portion of the work support 3, see Fig. I, which main sump also receives the drip oil from the drive shaft bearings 10 and 11 and from the rotary eccentric actuators 46. It will thus be seen that all the moving parts within the elevated portion 1 of the machine and in the head 5 are automatically lubricated by gravitational flow of oil from the reservoir 51.

In order that the oil collected in the main sump 87 may be returned from time to time to the supply reservoir 51, there is provided a hand pump means shown in Figs. I, II, IV and V, as comprising a piston 88 which is movable up and down within a cylinder 89 integrally formed with the rear end wall 15 of the elevated frame portion 1. As shown in Fig. V, the rod 90 of the piston 88 passes through a plug or head 91 which closes the cylinder 89 and which is removably secured by a set screw 92. A port 93 in the plug or head 91 permits the air to escape from the upper part of the cylinder 89 during operation of the pump. At the top, the piston rod 90 is provided with a hand knob 94 by which it can be grasped for the purpose of actuating the pump. Connecting into the bottom of the cylinder 89 is a screw nipple 95 with an incorporated spring-pressed ball check valve 96, which opens under suction; and leading downwardly from said nipple is a tube 97 which terminates in a screen or filter head 98 submerged in the oil within the main sump, see Fig. I. Near its bottom, (Fig. IV) the cylinder 89 communicates, by way of a duct 99 in the wall 15 of the machine frame with the chamber 48 at the rear end of the shaft 7, within

which duct is a spring pressed ball check valve 100 that opens during the pressure strokes of the piston 88. Thus as the piston 88 is raised, oil is drawn up from the main sump 87 through the tube 97 into the pump cylinder 89, the check valve 96 opening to permit such flow but the check valve 100 remaining closed. On the down stroke of the piston 88, the oil is forced from the pump cylinder 89 through the duct 99 and past the check valve 100 and into the duct 47 in the drive shaft 7 via the chamber 48. After the shaft 7 is filled, the excess oil passes from the chamber 48 through the ducts 55 and 54 (Fig. I) into the reservoir 51 in which it is accumulated for reuse.

Having thus described our invention, we claim:

1. In a sewing machine, a frame having a tubular horizontal portion with a hollow head projecting laterally therefrom; a needle bar guided in the head; a longitudinally-extending tubular drive shaft journaled in a bearing within the tubular frame portion; a gravity oil supply reservoir in communication with the interior of the shaft from which oil is conducted by way of a lateral port to the bearing; a closed housing interiorly of the elevated frame portion with a sump for receiving the overflow oil from the bearing; a transverse shaft extending into the closed housing through another bearing; a pair of gears connecting the two shafts within the housing and dipping into the oil from the sump in the latter to lift it to the transverse shaft bearing; a sump in the head for catching the overflow oil from the last mentioned bearing; operating connections between the transverse shaft and the needle bar lubricated with oil taken from the sump within the head; a main sump for receiving the overflow oil from the sump in the head; and means for returning the oil from the main sump to the reservoir.

2. In a sewing machine, a frame having an elevated tubular horizontal portion with a laterally projecting hollow head, and a hollow work support whereof the free end underreaches the head; a needle bar guided in the head; a longitudinally-extending tubular drive shaft journaled in a bearing within the elevated frame portion; a gravity flow oil supply reservoir in communication with the interior of the shaft from which oil is conducted by way of a lateral port to the bearing; a closed housing interiorly of the elevated frame portion with a sump for receiving the overflow oil from the bearing; a transverse shaft extending into the closed housing through another bearing; a pair of gears connecting the two shafts within the housing and dipping into the oil from the sump in the latter and lifting it to the transverse shaft bearing; a sump in the head for catching the overflow oil from the last mentioned bearing; operating connections between the transverse shaft and the needle bar lubricated with oil taken from the sump within the head; a main sump for receiving the overflow oil from the sump in the head; and means for returning the oil from the main sump to the reservoir.

3. In a sewing machine, a frame having an elevated tubular horizontal portion with a laterally-projecting hollow head, and a hollow work support whereof the free end underreaches said head; a needle bar guided in the head; a longitudinally extending tubular drive shaft journaled in a bearing within the elevated frame portion; a gravity flow oil supply reservoir in communication with the interior of the shaft from

which oil is conducted by way of a lateral port to the bearing; a closed housing interiorly of the elevated frame portion with a sump for receiving the overflow oil from the bearing; a transverse shaft extending into the closed housing through another bearing; a pair of gears connecting the two shafts within the housing and dipping into the oil in the sump to lift to the transverse shaft bearing; a sump in the head for catching the overflow oil from the last mentioned bearing; operating connections between the transverse shaft and the needle bar lubricated with oil taken from the sump within the head; a main sump within the work support for receiving the overflow from the sump in the head; and means for returning the oil from the main sump to the supply reservoir.

4. In a feed-off-the-arm sewing machine, a frame having an elevated tubular horizontal portion with a laterally projecting head, and a hollow work supporting arm connected at one end through a vertical tubular portion to said elevated portion with its free end underreaching said head; a needle bar guided in the head; a longitudinally-disposed tubular drive shaft journaled in a bearing within the elevated frame portion; complementary stitch forming and feeding means within the work supporting arm; separate rotary actuators on the drive shaft with operating connections extending down through the vertical tubular portion of the frame to the complementary stitch forming and feeding means; a gravity flow oil reservoir in communication with the interior of the drive shaft from which latter oil is conducted by way of individual ports respectively to the bearing and to the rotary actuators aforesaid; a closed housing interiorly of the elevated frame portion with a sump for receiving the overflow oil from the elevated portion; a transverse shaft extending into the closed housing through another bearing; gears connecting the two shafts within the housing and dipping into the oil from the sump in the latter and lifting it to the transverse shaft bearing; a sump in the head to catch overflow oil from the last mentioned bearing; operating connections between the transverse shaft and the needle bar lubricated with oil taken from the sump in the head; a main sump in the work supporting arm receiving the overflow oil from the rotary actuators on the main shaft and from the sump in the head; and

means for returning the oil from the main sump to the reservoir.

5. In a sewing machine, a frame having a tubular horizontal portion with a completely closed hollow head above a hollow work support; a needle bar guided in the head; a longitudinally tubular drive shaft; a bearing within the elevated frame portion having a hollow in communication with the interior of the shaft; a gravity flow oil reservoir within the tubular frame portion above the shaft from which oil is conducted by way of a lateral port to the bearing; a sump formed by a depression at the bottom of the head receiving the overflow oil from the bearing; mechanism wholly above the sump whereby the needle bar is actuated from the drive shaft including a member which intermittently dips into the oil in the sump to lubricate the mechanism by splash action; a main sump within the work support receiving the overflow from the sump in the head; and means for elevating the oil from said main sump to the hollow bearing to fill the hollow of the shaft and the reservoir.

6. In a sewing machine, a frame having a tubular horizontal portion with a completely closed hollow head, above a hollow work support; a needle bar guided in the head; a longitudinally tubular drive shaft; a bearing within the elevated frame portion having a hollow in communication with the interior of the shaft; a gravity flow oil reservoir within the elevated frame portion above the shaft from which oil is conducted by way of a lateral port to the bearing; a sump formed by a depression at the bottom of the head receiving the overflow oil from the bearing; mechanism wholly above the sump whereby the needle bar is actuated from the drive shaft including a member which intermittently dips into the oil in the sump to lubricate the mechanism by splash action; a main sump within the work supporting arm receiving the overflow from the sump in the head; and means for elevating the oil from the main sump to the hollow bearing to fill the hollow of the shaft and the reservoir including a hand pump whereof the cylinder is integrally formed with the machine frame at the top, a conduit connecting the pump cylinder with said main sump, and a piston within the cylinder having an actuating projection accessible exteriorly of the machine frame.

50
